UNITED STATES PATENT OFFICE.

CHARLES A. SELLON, OF HALLECK, CALIFORNIA.

MAGNETIC ORE-SEPARATOR.

973,984.

Specification of Letters Patent. Patented Oct. 25, 1910.

Application filed November 16, 1909. Serial No. 528,416.

To all whom it may concern:

Be it known that I, CHARLES A. SELLON, a citizen of the United States, residing at Halleck, in the county of San Bernardino and State of California, have invented a new and useful Magnetic Ore-Separator, of which the following is a specification.

This invention relates to an improved sluice box for the magnetic separation of gold, tin, tungsten and other heavy metals contained in black or magnetic sands.

The invention has for one of its objects to improve the construction and operation of apparatus of this character so as to be comparatively simple and inexpensive to manufacture, reliable and efficient in use, and so designed as to effect a material saving in metals.

Another object of the invention is the provision of a novel arrangement of magnetic plates over which pass the sands that contain gold and other metals with the magnetic particles, in combination with longitudinal partitions for effecting the even distribution of the sands over the plates.

Another object is the employment of means for testing the values of the sand that is carried by the water from the magnetic plates to determine the operative conditions.

With these objects in view and others, as will appear as the description proceeds, the invention comprises the various novel features of construction and arrangement of parts which will be more fully described hereinafter and set forth with particularity in the claims appended hereto.

In the accompanying drawings, which illustrate one embodiment of the invention, Figure 1 is a perspective view of the improved sluice trough. Fig. 2 is a central longitudinal section thereof. Fig. 3 is a plan view. Fig. 4 is a vertical transverse section. Fig. 5 is a fragmentary perspective view of one of the secondary partitions. Fig. 6 is a detail sectional view showing the manner of supporting the secondary partitions.

Similar reference characters are employed to designate corresponding parts throughout the views.

Referring to the drawings, A designates the supporting frame of any suitable construction for the sluice trough B through which the metal-carrying sands flow. This trough may be of any approved construction and consists of side plates 1 and a bottom 2

on which are supported main and secondary partitions 3 and 4, there being one central main partition in the present instance and two or more secondary partitions at opposite sides of the main partition, although the number of partitions may be varied, as desired. These partitions serve to evenly distribute the sands over the magnetic plates 5 on the bottom of the trough, as the sands are carried down the trough by the water. Where the magnetic plates are located, the trough is open as indicated at 6, Fig. 2, and directly under the plates are electro-magnets 7. Each plate extends between the main partition and side wall of the trough and is of the same length as the opening 6. The magnetic plates are each constructed of a piece of sheet iron or other magnetic metal which has its longitudinal marginal portions doubled under so that the plate will be of two thicknesses, being separated by a sheet of paper, cloth or the like 8, as clearly shown in Fig. 4. It has been found that with this arrangement, the magnetic attraction is more evenly distributed than when a single sheet of metal is used. The pole pieces 9 of the magnets are extended transversely of the plates 5 so as to be approximately the same width as the latter, and these magnets may be of any desired strength according to the conditions of service. In the present instance, a pair of magnets is shown under each plate and located adjacent the ends thereof, the magnets being supported in any suitable manner on the frame A and under the trough B. The portion of the trough where the magnetic plates are located has a copper lining 10 on the central partition and side walls of the trough, the lining being soldered to the magnetic plates. The secondary partitions are also preferably of copper and are removable for facilitating the cleaning of the gold-bearing sands which are arrested on the magnetic plates by the magnets. These partitions 4, as shown clearly in Figs. 5 and 6, are reinforced at their upper ends by a bead a having a stiffening wire b and provided with laterally-extending base lugs 12 which have pins 13 that are adapted to engage in sockets 14 in the copper strips 15 that extend across the trough bottom at the ends of the magnetic plates. Obviously, any other means may be employed for supporting these removable partitions.

At the lower ends of the magnetic plates, an amalgamated plate 16 is removably fitted

in the trough for testing purposes, whereby it is possible to determine whether gold is escaping by being conducted off the magnetic plates with the water. This amalgamated 5 plate is used only occasionally in order to prevent loss of quicksilver. The plate 16 rests on the bottom of the trough and has side walls 17. This amalgamated plate fits under the copper lining 19 and bottom strip 10 15, which are supported a way from the side walls and bottom of the trough, respectively, so as to provide a recess or pocket 18 for receiving the upper end of the amalgamated plate or testing device 16, there being a pack- 15 ing strip 19 in this recess for preventing water from leaking backwardly under the copper lining and strip and flowing out through the opening 6 in the bottom of the trough. The testing device or amalgamated 20 plate may thus be securely held in place without requiring special fastenings.

In practice, the sluice trough is supplied with black sand in any suitable manner, which is carried down by the water through 25 the passages formed between adjacent partitions, and the outermost partitions and side walls of the trough. The magnets, being energized, will cause the magnetic particles to arrest the gold and the like which flows 30 down the trough, the gold and particles to be separated moving along the bottom of the trough because of their being heavier than the magnetic particles, so that the latter will entrap the gold and the like on the 35 magnetic plates by the lines of force from the electromagnets. After the trough has been operating a suitable time, the amalgamated plate is inserted to make a test for gold losses. When a loss of gold appears, 40 the flow through the trough is stopped and the magnets deenergized. The removable partitions are then taken out so as to permit the arrested particles on the magnetic plates to be scraped out of the trough. After the 45 trough is cleaned, the partitions are replaced and the amalgamated plate removed so that another charge of metal particles to be separated can be supplied to the trough after the magnets are again energized, the 50 operations previously described being repeated.

In wiring the magnets, it is important that the circuit connections with the magnetic poles be such that those under one 55 plate will be all of the same polarity but different from the magnetic poles under the other plate. That is to say, if the magnetic poles under one plate are positive, those under the other plate must be negative.

60 When there is not sufficient proportion of magnetic particles in the sand to insure effective operation, iron filings or equivalent material can be mixed with the metal bearing sand so that precious metals can be better separated.

From the foregoing description, taken in connection with the accompanying drawings, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the claims appended hereto.

Having thus described the invention, what I claim as new, and desire to secure by Letters Patent, is:

1. The combination of a trough, a magnetic plate arranged in the bottom thereof and consisting of sheet metal of double thickness with a non-magnetic filling, and magnets arranged on the plate.

2. The combination of a trough, a magnetic plate arranged in the bottom thereof and consisting of sheet metal of double thickness with a non-magnetic filling, magnets arranged under the plate, and removable partitions extending longitudinally of the trough and arranged on the plate.

3. The combination of a trough having a magnetic bottom plate, magnets arranged under the plate, socketed transverse strips at the ends of the plate, partitions extending longitudinally of the plate, and lateral lugs at the lower edges of the partitions having depending pins to engage the socketed strips.

4. The combination of a trough, a plurality of magnetic plates mounted in the bottom thereof, a main partition extending between the plates and longitudinally of the trough, secondary partitions mounted on the plates, and magnets under each plate, each plate consisting of a sheet of magnetic material doubled longitudinally and having a non-magnetic filling disposed between the doubled portions.

5. The combination of a trough having a metal lining which is spaced from the trough to form a recess, an amalgamated plate removably fitted in the trough at a point below the lining and engaging the recess, a magnetic plate above the amalgamated plate fixed in the trough, and magnets under the magnetic plate.

6. The combination of a trough having an opening in its bottom, magnetic plates over the opening each doubled under with its longitudinal edges approximately meeting at the center, a main partition extending longitudinally of the trough and between the plates, a non-magnetic lining covering the side walls of the trough and the partition and extending across the bottom of the trough at the ends of the opening, secondary

partitions supported in the bottom of the trough and extending longitudinally of the magnetic plates, and magnets secured under the magnetic plates.

- 5 7. The combination of a trough having an opening in its bottom, a main partition extending longitudinally of the opening, a non-magnetic lining covering the side walls of the trough and the partition and extending 10 across the bottom of the trough at the ends of the opening, secondary partitions supported in the bottom of the trough and extending longitudinally of the magnetic plates, magnets secured under the magnetic

plates, the portion of the lining at the lower 15 end of the opening being raised at the bottom of the trough for providing a recess, a packing strip for preventing leakage through the recess, and an amalgamated plate adapted to be fitted in the trough below the magnetic plates and to enter the said recess.

In testimony, that I claim the foregoing as my own, I have hereto affixed my signature in the presence of two witnesses.

CHARLES A. SELLON.
